UNITED STATES PATENT OFFICE.

HARRY O. DAVIDSON, OF CLEVELAND, OHIO, ASSIGNOR TO THE HYDRAULIC PRESSED STEEL COMPANY, OF CLEVELAND, OHIO, A CORPORATION OF OHIO.

SEWER-FORM.

1,269,164.

Specification of Letters Patent. Patented June 11, 1918.

Application filed September 5, 1916. Serial No. 118,361.

To all whom it may concern:

Be it known that I, HARRY O. DAVIDSON, a citizen of the United States, residing at Cleveland, in the county of Cuyahoga and State of Ohio, have invented a certain new and useful Improvement in Sewer-Forms, of which the following is a full, clear, and exact description, reference being had to the accompanying drawings.

10 This invention relates generally to sewer forms or molds and more particularly to one intended for use in the building of circular sewers of small diameters, although the same principle can be applied to forms or molds for large sized sewers.

15 The invention may be further defined as belonging to that class of forms or molds in which a plurality of sections are arranged end to end to produce a form or mold of the desired length, and the cement or concrete then poured around the same, properly tamped and permitted to harden. After the cement or concrete has "set" sufficiently, the form is collapsed from the interior, 20 withdrawn from the molded sewer and reset for a further length or sewer formation thereby permitting a continuous or monolithic sewer to be made.

25 The object of my invention is to provide, in a mold of this character, a novel construction of mold or form section which can be quickly and easily set up or collapsed, and another object is to provide a novel form of connecting means which will connect the sections upon the interior and brace them at their point of connection and still be readily detachable and collapsible when desired.

30 With these objects in view and certain others which will be made apparent as the description proceeds the invention consists in the novel features of construction and the manner of combining the same and which will be fully described hereinafter 35 and pointed out in the claims.

35 In the drawings forming a part of this specification, Figure 1 is a sectional elevation illustrating the manner of collapsing the rings and plates of the form or mold; Fig. 2 is a similar view showing the rings and plates in their expanded or molding 40 positions; Fig. 3 a longitudinal sectional view on the line 3—3 of Fig. 2; Fig. 4 is a detail perspective partly in section illustrating the manner of uniting the ends of the

mold sections by means of an interior ring; Fig. 5 is a detail perspective view illustrating the manner of fastening the abutting edges of the plates from which the mold section is made; Fig. 6 is a detail perspective view of the hinge joint between the ring section; and Figs. 7, 8, 9 and 10 are detail views illustrating the latch for uniting the ring sections, the latch being shown in its open and closed positions, respectively.

45 In practice I prefer to make each mold section from a plurality of longitudinally curved plates, such plates being so curved that when their longitudinal edges are placed together they make a complete circular or tubular form section. In the drawings which I have chosen to illustrate one embodiment of my invention, there are shown three curved plates A¹, A² and A³ which when placed together will make a tubular or circular form section, and for the purpose of maintaining these plates in their proper position I not only lock their meeting edges but also arrange interior bracing or strengthening rings at the junction of two form sections, and in practice I prefer to make these rings sectional as shown consisting of the portions B¹, B² and B³, the portion B² being hinged to the portion B¹ and B⁴, and the portion B³ hinged to the end of B¹ at B⁵. These ring sections are so curved that when opened out and their free ends connected a complete circular ring will be provided as shown in Fig. 2.

50 Each plate A¹, A² and A³ has a metallic strip C welded or otherwise secured along one edge thereof, and projecting beyond the edge of the plate as shown. The projecting portion of each strip is made with a plurality of apertures, through which headed studs D carried near the edge of the abutting plate are adapted to pass, and a latch E is pivotally connected to the plate C in line with each aperture in order to engage the headed stud as shown in Figs. 3 and 5, thereby securely connecting together the longitudinal edges of the plates. By means of this construction the three curved plates are locked along their longitudinal edges and constitute one section of the form or mold.

55 The sections so made are arranged end to end and the sectional rings are arranged at the joint between two mold sections and upon the interior thereof for the double pur-

pose of bracing the structure at this point and uniting the mold sections. The ring sections are formed of channel iron as shown and are hinged together as previously described, the free ends of the sections B^2 and B^3 being cut upon a bevel, as shown at R , R' , respectively, so that when the sections are opened out, these beveled ends will substantially engage each other, providing a smooth joint and, while the section B^2 is swung inwardly about the center B^4 , it will clear the end of the section B^3 .

For the purpose of connecting these ends I employ a pivoted latch F which is connected to a channeled support G welded to the ring within the same, said latch having a notch F' which is adapted to engage the headed stud H carried by a channeled support I welded in the end of the other ring section; and in order to prevent any lateral movement at this joint I provide plates K upon opposite sides of the ring sections and projecting beyond the beveled ends thereof sufficiently to overlap the joint, as most clearly shown in Figs. 1 and 2. Rings constructed in this manner can be readily set up or collapsed as desired.

For the purpose of uniting the end sections by means of the rings, I provide each ring section with a pair of latches L slidably connected to the ring in the channel portion thereof, and having slots L' in their ends for engagement with the headed studs M carried by the plates of the form section at each end and projecting inwardly through the ring, and it is obvious that after the latches L have been brought into engagement with the headed studs M , the sections of the mold will be securely locked together and to the interior bracing ring thereby completing the construction of the mold or form inasmuch as the plates are locked together both longitudinally and transversely and are at the same time held in their proper positions ready to have the cement or concrete poured around the exterior thereof.

When it is desired to collapse the mold, the latches L are first opened, then the latches F , and then the ring collapsed. The plate sections can then be unlatched and drawn inwardly by means of a turn buckle N and hook rods O which engage lugs P attached to the interior of the plates; but if desired the turnbuckle can be dispensed with and the plates collapsed by disconnecting them at all three points. When a turnbuckle is used it is only necessary to disconnect one plate and draw the ends of the other two plates inwardly as illustrated in Fig. 1.

After the form has been collapsed it can be withdrawn from the molded sewer, set up again in position and more cement or concrete placed about the same for the purpose of molding another portion of the sewer.

By means of a device such as herein shown and described a continuous or monolithic sewer can be quickly and easily molded, the mold or form being quickly and easily set up and collapsed as needed and effectively serving its purpose as a mold when properly assembled.

Having thus described my invention, what I claim is:—

1. A form comprising a plurality of curved plates and means for detachably locking said plates together along their longitudinal edges, an interior ring composed of a plurality of sections hinged together, means for detachably connecting the ends of said hinged sections, and means for connecting said ring sections to the ends of the curved plates.

2. A form comprising a plurality of curved plates and means for detachably locking said plates together along their longitudinal edges, an interior ring composed of a plurality of sections hinged together, a latch for connecting the ends of said hinged sections, and means for connecting said ring sections to the ends of the curved plates.

3. In a form, a ring composed of a plurality of sections hinged together, the end of one section having a laterally movable latch connected thereto and the end of the opposite section having a stud adapted to be engaged by said latch, together with means carried by one section and adapted to engage the opposite section to prevent lateral displacement of said sections.

4. A form comprising a plurality of curved plates and means for locking said plates together along their longitudinal edges, an interior ring composed of a plurality of sections hinged together, a latch for connecting the ends of said hinged sections, and means for connecting said ring sections to the curved plates.

5. A form comprising a plurality of curved plates, each having a strip overlapping one edge, said strip being apertured, the opposite edge of each plate having headed studs adapted to engage the apertured strip and a latch carried by said strip and adapted to engage said headed stud for the purpose specified.

6. In a form, a ring composed of a plurality of sections hinged together, means carried at the end of one section and adapted to engage the opposite section to prevent lateral displacement of said sections, and a latch carried by said positioning means and adapted to engage a stud upon the opposite section for the purpose of locking said positioned ends together.

7. In a form, a ring composed of a plurality of sections hinged together, the end of one section being beveled and provided with a latch and the end of another section being correspondingly beveled and provided

with a headed stud, and guide plates upon opposite sides of one end to prevent lateral displacement.

8. A form comprising a plurality of curved plates, each having an apertured strip along one edge and headed studs upon the opposite edge, said apertured strips carrying latches, and a ring composed of a plurality of sections hinged together, the end of one section having a latch and the end of another section having a headed stud adapted to be engaged by said latch, each ring section having a longitudinally slotted latch adapted to engage a headed stud carried by a plate section at the end thereof.

9. A form of the kind described comprising a plurality of curved plates, means for uniting their longitudinal edges, a sectional ring adapted to be arranged within said plates and connected thereto, and a turn-buckle and rods connecting the plates adapted to operate as specified.

10. A form of the kind described com-

prising a plurality of curved plates, and a plurality of sectional rings, means for uniting the edges of said plates and independent means for uniting the ends of said plates and sections of rings. 25

11. A form comprising a plurality of curved plates, each carrying a latch upon one longitudinal edge and a headed stud adjacent the opposite longitudinal edge, said curved plates being adapted to be interlocked to provide a form section, and a ring composed of a plurality of sections hinged together, the end of one section having a latch adapted to engage means upon the opposite meeting ring section, said ring being of a width to overlap the joint of two form sections, said ring carrying means for engagement with fastening means carried upon the end of the section. 30 35 40

In testimony whereof, I hereunto affix my signature.

HARRY O. DAVIDSON.
